UNITED STATES PATENT OFFICE.

JOHN SELLER, OF BROOKLYN, NEW YORK.

AUTOMATIC WINDOW LATCH.

Application filed October 15, 1927. Serial No. 226,284.

This invention relates to window latches or fasteners and aims to provide a novel construction in devices of the above mentioned type, whereby the upper and lower window sashes may be automatically and securely locked by simple pressure of the thumb or finger on a finger piece forming a part of the construction and readily unlocked by manipulating the said finger piece to partially 5 turn a bolt member on its axis.

An object of the invention is to provide a simple inexpensive device for accomplishing the above results possessing features intended to obviate some of the objections present in 15 the prevailing styles of construction for the same purpose now in general use.

Features of the invention are found in a suitably formed casing adapted to be secured to the upper rail of the lower window sash 20 and a keeper plate adapted to be fastened to the lower rail of the upper sash said keeper plate being provided with a central circular opening having flared walls and side slots 25 communicating with said opening, the said casing being provided with end walls, one wall having a circular opening and the other a squared one, through which a bolt, having round and square portions is slidable, means being provided to automatically rotate said 30 bolt through a limited arc when a round portion is in registration with a squared opening of the corresponding end wall of the casing.

The invention has for its further objects to 35 provide certain other novel features, all of which will be more clearly defined in the following detailed description. The arrangement of the parts may be varied considerably, the present embodiment illustrating the invention now thought to be the best form, but it will be understood that many refinements may be made in the device without departing from the invention claimed.

In the drawings:

Fig. 1 is a perspective view of the improved 45 automatic window latch applied to a window.

Fig. 2 is a central longitudinal section 50 thereof showing the parts unlocked in full lines and locked in dotted lines.

Fig. 3 is a cross sectional elevation on the line 3—3 of Fig. 2.

Fig. 3^a is a face view of the keeper.

Fig. 4 is a similar view, but showing a modified 55 form of latch bolt.

Fig. 5 is another similar view and showing a further modified form of latch bolt.

Referring in detail to the drawings I apply a casing 10, to the upper rail 11 of the low window sash and a keeper 12, to the lower 60 rail 13 of the upper sash. The parts are preferably applied by screws or other fastening devices 14.

The casing is open at the bottom and has 65 end walls 15 and 16 the former preferably having a squared opening 17 therethrough and the latter being formed with a circular opening 18.

A latch bolt 19 operates in the openings just 70 described and is of round cross section for about half of its length from its locking end as shown at 20, and terminates in a squared portion 21, which normally engages the squared opening 17 and beyond the squared portion is another but shorter rounded portion 22 from which a radial pin 23 projects 75 from one side, which acts to limit the rotary or turning movement of the bolt 19 by contact with one of a pair of stop pins 24 and 25. A head 26, having a finger piece 27 is 80 fixed to the outer end of the bolt 19, by which said bolt is manipulated and a cross pin 28 is carried by said bolt near the locking end thereof and which normally is drawn against the casing 10 by the urge of a spiral spring 85 29, having one end held by a screw 29 threaded into the end 16 of the casing and the other end held by a screw 30 threaded into the bolt 19. This spring is normally slightly compressed to urge the latch bolt outwardly and 90 is also charged torsionally to automatically spin the latch bolt through a quarter turn when the squared portion 21 clears the squared opening in the end walls 15 of the casing as the latch bolt is moved backwardly 95 in the locking operation, the pin 25 serving to arrest its spinning movement which takes place after the cross pin 28 on the rear end of the latch bolt has passed through aligned slot 31, bisecting a central flared opening 32 100 in the keeper 12, the locking end of the bolt 19 being conical as at 33, for free passage backwardly and for adjusting small irregularities in the cooperation of the parts. The spinning movement of the bar 19 carries the cross pin around 90° where it is stopped at a 105 right angle to the slots 31, thus securely locking the parts and when it is desired to unlock the said parts, the finger piece is grasped and the bolt 19 forced inwardly until the rounded

110

portion is in the square opening 17, when the bolt can be turned backward 90° to register the cross pin 28 with the slots 31 when the spring will snap it back out of engagement 5 with the keeper as in Fig. 2.

It should be understood that the squared portion 21 is engaged by the squared opening 17 at all times except when the latch bolt is in its rearmost position so that no turning movement can take place only at that time and then said movement is limited by the stop pins 24 and 25.

In Fig. 4 I show a modified form in which I may provide the end 15 of the casing with 15 a tongue 34 and the shaft may have short grooves 35 arranged at 90° , the spin of the latch bolt taking place when a circumferential groove 36 registers with the tongue 34.

In Fig. 5, I show another form in which 20 the shaft 19 may have a short rib or feather 37, slidably in one or the other of grooves 38 in wall 15 of the casing, the spin of the latch bar taking place when the rib or feather clears the said wall in its sliding movement.

25 What I claim as new, is:—

1. In a window latch, a housing and a keeper, said housing having end walls, one provided with a circular opening and the other with a squared one, a bolt operable in 30 said openings, a stop pin on one end of said bolt and a securing pin on the other, and means for automatically causing the bolt to turn when the securing pin thereon has been passed through said keeper to secure the 35 parts.

40 2. In a window latch, a housing and a keeper, said housing having end walls, one provided with a circular opening and the other with a squared one, a bolt operable in said openings, a stop pin on one end of said bolt and a securing pin on the other, and means for automatically causing the bolt to turn when the securing pin thereon has been 45 passed through said keeper to secure the parts, said means comprising a longitudinally tensioned and torsionally charged spring encircling said bolt.

50 3. In a window latch, a housing and a keeper, said housing having end walls, one provided with a circular opening and the other with a squared one a bolt operable in said openings, a stop pin on one end of said bolt and a securing pin on the other, and means for automatically causing the bolt to 55 turn when the securing pin thereon has been

passed through said keeper to secure the parts, attached one end to the housing and the other end to the bolt.

4. A window latch comprising a housing and a keeper, said keeper being provided with 60 a central opening and communicating slots, said housing having end walls, one having a round opening, the other a squared one, a bolt operating in said openings and having rounded portions and a square portion normally engaging the said square opening, said bolt having a finger piece, a stop pin and a securing pin, and means for causing said securing pin to engage said keeper when it passes the opening therein.

5. A window latch comprising a housing and a keeper, said keeper being provided with a central opening and communicating slots, said housing having end walls, one having a round opening, the other a squared one, 75 a bolt operating in said openings and having rounded portions and a square portion normally engaging the said square opening, said bolt having a finger piece, a stop pin and a securing pin, and means for causing said securing pin to engage said keeper when it passes the opening therein, said means comprising a longitudinally tensioned and torsionally charged spring.

6. In a window latch, a housing and a keeper, said housing having end walls provided with openings, a bolt operable in said openings, a stop pin on one end of said bolt and a securing pin on the other, means on said bolt and in one of said end walls associated with its opening, adapted to prevent the passing of the bolt except in a position determined by said stop pin, and means for automatically causing the bolt to turn when the securing pin thereon has been passed 95 through said keeper to secure the parts.

7. In a window latch as set forth in claim 6, said means to prevent the passing of said bolt through its opening, except in a predetermined position of the same, comprising co-operating square portions on said bolt and in the side wall.

8. In a window latch as set forth in claim 6, said means for turning the bolt comprising a longitudinally tensioned and torsionally charged spring encircling said bolt.

Signed at New York, in the county of New York and State of New York, this 7th day of October, A. D. 1927.

JOHN SEILER.
